(57) **CLAIM**

We claim the ornamental design for front portions of housing and trigger components of a latch assembly, as shown and described.

DESCRIPTION

FIG. 1 is a perspective view of front portions of housing and trigger components of a latch assembly showing front, left and end features of our new design;

FIG. 2 is a front view thereof;

FIG. 3 is a left side view thereof, it being understood that a right side view is identical hereto but a mirror image reversal hereof; and,

FIG. 4 is an end view thereof, it being understood that a view of the opposite end thereof is identical hereto but a mirror image reversal hereof.

The broken line disclosure in the drawings is provided for illustrative purposes only and forms no part of the claimed design.

The broken lines, which define the bounds of the claimed design form no part thereof.

1 Claim, 2 Drawing Sheets
